SLIDE BOLT DOOR LATCH

Ray Raymond, 3157 McKinley Blvd.,
Sacramento, Calif. 95816

Filed Feb. 5, 1968, Ser. No. 10,455

Term of patent 14 years

(Cl. D50—5)

FIGURE 1 is a front perspective view of a slide bolt door latch, with the bolt in projected position, showing my new design;

FIGURE 2 is a side elevational view, showing the bolt in projected position, the opposite side being substantially similar in appearance;

FIGURE 3 is a front end elevational view, the opposite end being substantially similar in appearance; and,

FIGURE 4 is a top plan view, showing the bolt in retracted position, the fragmentary outline of a door being shown for illustrative purposes only, the view of the bottom being substantially similar in appearance.

The dominant features of my design reside in the portions shown in full lines.

I claim:

The ornamental design for a slide bolt door latch, as shown and described.
